KAKUJI TAKAHASHI, OF SAN FRANCISCO, CALIFORNIA.

FASTENER FOR BROOCHES AND THE LIKE.

1,042,291.

Specification of Letters Patent. Patented Oct. 22, 1912.

Application filed January 4, 1912. Serial No. 669,429.

To all whom it may concern:

Be it known that I, KAKUJI TAKAHASHI, a subject of the Emperor of Japan, residing at San Francisco, in the county of San Francisco and State of California, have invented new and useful Improvements in Fasteners for Brooches and the Like, of which the following is a specification:

The present invention relates to improvements in fasteners for securing brooches, badges, and the like, or for attaching watches on the outside of ladies' dresses.

It is a common practice for ladies to secure their watches by means of a pin or fastener pinned to the outside of the dress, and the common construction of such fastener has been to provide a rotary retainer for the pointed end of the pin, which retainer in one position allows said pointed end to enter therein, while in another position it prevents its escape therefrom. It is found in practice that this retainer is liable to turn accidentally in its bearing, so that it moves into the position in which the pin is released, thereby greatly diminishing the efficiency of the fastener. A further objection to the present construction of such fasteners is that the point of the pin, projecting through the retainer, is apt to enter the fabric of the dress. When the wearer unloosens the fastener, she does so by bringing the pointed end of the pin to the front to enable the retainer to be more easily turned with the finger. But if the pointed end of the pin has entered the fabric and engaged one or two of the threads thereof, then the effect of bringing this pointed end forward is to pull out of the fabric the threads so engaged by said pointed end, thus greatly damaging the fabric.

The object of my present invention is to avoid the above defects.

In the accompanying drawing, Figure 1 is an enlarged bottom plan view of the fastener; Fig. 2 is a side view thereof, partly in longitudinal section; Fig. 3 is a greatly enlarged bottom plan view of the retaining means, the bearing therefor being shown in section; Fig. 4 is a cross-sectional view thereof on the line 4-4 of Fig. 3; Fig. 5 is an end view thereof in the closed position; Fig. 6 is a diagrammatic sectional view.

Referring to the drawing, 1 indicates the body of a fastener, to which is secured a pivot casing 2, having a pivot 3, upon which

is pivoted the flattened enlarged terminal portion of a pin 4.

5 indicates a flat spring, of which one terminal portion is soldered or otherwise suitably secured, as shown at 6, to the body 1 of the pin, and the other end bears against a flattened part 7 of the edge of said enlarged terminal portion, so that the pressure of the spring tends to turn the pin on its pivot into the position shown in Fig. 2. The outward movement of the pin is, however limited by the abutment of a portion 8 of the casing 2 against the back of the pin.

9 indicates a cylindrical bearing attached, as shown at 10, to the body 1 of the fastener. Within the cylindrical inner surface of said bearing can rotate a cylindrical retainer 11, extending at each end beyond the bearing and having formed integral therewith at the inner end a flange 12, which abuts against the end of the bearing, and at the outer end an arm 13 by which the retainer can be turned in the bearing. The outer end of said retainer is closed, as shown at 14, but the inner end is open. There is also formed in the cylindrical body of the retainer a longitudinal opening 15 adapted, by the rotation of the retainer, to be aligned with a similar opening 16 in the bearing, both of these openings being sufficiently large to permit the pointed terminal portion of the pin to be passed therethrough into the interior of the retainer.

The recess to receive the pin within the retainer is formed with parallel walls and semi-cylindrical bottom, the axis of which is eccentric to the retainer, so that the pin received within the retainer, is, when the retainer is in its closed position, on the side of said axis opposite to the body of the fastener. In this position the spring pressure prevents the retainer from turning, not only by creating frictional resistance between the pin and the retainer and also between the retainer and the bearing, but also positively, for it will be seen that, when the retainer is turned from this closed position, the pointed end of the pin is thereby pushed inward toward the body of the fastener against the spring pressure. Consequently the spring pressure resists this rotary movement. Hence the retainer is held very securely against rotation, thereby very greatly increasing the security afforded by the fastener.

It may be noted that with the above construction of retainer, the spring could be omitted, and the same general result obtained by the mere outward pressure on the 5 pin of the fabric to which the fastener is secured.

A further important improvement resides in making the retainer closed at the outer end. When fasteners of this general character are used to secure watches, or other articles on the outside of ladies' dresses, if the outer end of the retainer is open, it frequently happens that the pointed end of the pin penetrates the fabric of the dress. When 10 this is the case, since the fastener is loosened by moving the retainer end of the fastening forward, so as to permit of manipulation of the retainer by the fingers, this forward movement causes the pointed end of the pin 15 to pull out the threads behind which it has penetrated into the fabric, thereby damaging the dress. In my present improvement 20 this result cannot occur.

I claim:—

In a fastener, the combination with a 25 body, and a pin pivoted thereto, a bearing secured to said body, a cylindrical retainer for the free end of the pin rotatable in said bearing, said bearing having a longitudinal opening to permit the free end of the pin to 30 pass therethrough and the retainer having a recess to receive said free end, the opening into said recess being adapted to register with the opening in the bearing, said recess being formed with parallel walls and a semi-cylindrical bottom and so formed that the semi-cylindrical bottom leaves a wall of less thickness adjacent thereto than at the sides of the retainer.

In testimony whereof I have hereunto set 40 my hand in the presence of two subscribing witnesses.

KAKUJI TAKAHASHI.
